UNITED STATES PATENT OFFICE

116,154

DESIGN FOR A SPOON OR OTHER ARTICLE OF FLATWARE

F. Russell Woodward, Attleboro, Mass., and Axel H. Staf, Providence, R. I., assignors to Gorham Manufacturing Company, Providence, R. I., a corporation of Rhode Island

Application April 19, 1939, Serial No. 84,380

Term of patent 14 years

To all whom it may concern:

Be it known that we, F. Russell Woodward and Axel H. Staf, citizens of the United States of America, of 32 Claflin Street, Attleboro, Massachusetts, and 205 Lenox Avenue, Providence, Rhode Island, respectively, have invented a new, original, and ornamental Design for a Spoon or Other Article of Flatware, of which the following is a specification, reference being had to the accompanying drawing, forming part thereof.

Figure 1 is a front elevation of a spoon showing our new design;

Figure 2 is a side view of the same, and

Figure 3 is a rear elevation of the spoon.

We claim:

The ornamental design for a spoon or other article of flatware, substantially as shown.

F. RUSSELL WOODWARD.
